(57) **CLAIM**

The ornamental design for a fashion hook, as shown and described.

DESCRIPTION

FIG. 1 is a perspective view of a fashion hook;

FIG. 2 is front elevation thereof;

FIG. 3 is a top view thereof;

FIG. 4 is a bottom view thereof;

FIG. 5 is one side view thereof; and,

FIG. 6 is another side view thereof.

The rear portion of the fashion hook is not visible during ordinary use and forms no part of the claimed design.
